UNITED STATES PATENT OFFICE.

JAMES W. McFARLAND, OF LOS ANGELES, CALIFORNIA.

RADIATOR CONSTRUCTION.

1,410,531.

Specification of Letters Patent. Patented Mar. 21, 1922.

Application filed July 2, 1920. Serial No. 393,628.

To all whom it may concern:

Be it known that I, JAMES W. McFARLAND, a citizen of the United States, residing at Los Angeles, in the county of Los Angeles and State of California, have invented new and useful Improvements in Radiator Constructions, of which the following is a specification.

This invention relates to radiator constructions of the type comprising a plurality of water cells arranged alongside one another in spaced relation.

It is the object of the invention to provide improved spacers between the water cells which are adapted to increase the circulation of air between the water cells.

The invention will be readily understood from the following description of the accompanying drawings, in which—

20 Figure 1 is a front elevation of a radiator constructed in accordance with the invention.

25 Fig. 2 is a fragmentary detail view of adjacent water cells of the radiator with the improved spacer interposed between the same.

Fig. 3 is a transverse section on the line 3—3 of Fig. 2.

30 Fig. 4 is a detail longitudinal section on the line 4—4 of Fig. 3.

Fig. 5 is a side elevation of the improved spacer.

In the present embodiment of the invention a usual radiator casing is shown at 1 having a radiator core mounted therein consisting of a plurality of vertical water cells arranged alongside one another in spaced relation. These cells may be of any well known or preferred construction and for the 40 purpose of illustration I have shown the cells as each comprising spaced walls 2 each having laterally off-set reverse bends 4 extending from opposite sides of the water cells in staggered relation lengthwise thereof. A water channel 5 is formed between the spaced walls comprising the water cell. The water cells are, preferably, arranged in parallel spaced relation with the off-sets 4 of adjacent cells which extend toward one 45 another arranged in staggered relation lengthwise of the cells.

The improved spacer provided between adjacent water cells, preferably, consists of plates 6 lying against one another and each 55 formed with laterally off-set reverse bends 7 projecting from opposite sides of the plates

6 in staggered relation lengthwise of said plates. When the spacer plates are interposed between adjacent water cells the lateral off-sets 7 are arranged to abut against 60 the walls 2 of the respective water cells with the lateral off-sets 4 of said water cells abutting against the plates 6 forming said spacers. When the parts are thus assembled the lateral off-sets 7 are, preferably, arranged midway between adjacent lateral off-sets 4 of wall 2 and longitudinally thereof.

The plates 6 between adjacent off-sets 7 are provided with rows of outwardly extending projections 8, each row of which, 70 preferably, includes a plurality of said projections arranged one beyond the other transversely of the spacer plates as clearly shown in Fig. 3. The ends of each of these projections are slotted as shown at 9 and the end tips of the projections are outwardly bent as shown at 10 to provide baffles arranged to guide the air passing along the spacer plates into the slots 9 for causing circulation of said air in the spaces 11 provided 80 between the opposite disposed projections 8 of the spacer plates lying against one another.

By the construction as thus set forth it will be seen that means are provided for 85 positively spacing the water cells of a radiator, said spacing means being so arranged as to induce circulation of air through the spaces between the plates forming said spacer means.

90 Various changes may be made without departing from the spirit of the invention as claimed.

What is claimed is:

1. A radiator construction comprising 95 spaced water cells, and spacer plates between said cells arranged face to face and having aligned offsets forming cooperating grooves in the contacting surfaces of said plates, the ends of said offsets being slotted 100 with the ends thereof outwardly bent to form baffles for guiding air through said slots and into the spaces formed between said spacer plates by said cooperating grooves.

105 2. A radiator construction comprising spaced water cells, and spacer plates between said cells arranged face to face and having alternate outwardly extending reverse bends projecting to said water cells, said spacer 110 plates also having aligned offsets forming cooperating grooves in the contacting surfaces

- of said plates, the ends of said offsets being open to permit the passage of air into the spaces formed between said spacer plates by said cooperating grooves.
- 5 3. A radiator construction comprising spaced water cells each having outwardly extending reverse bends, and spacer plates between said cells arranged face to face and having alternate outwardly extending re-
- 10 verse bends projecting to said water cells

between the reverse bends of the same, said spacer plates also having alined offsets forming cooperating grooves in the contacting surfaces of said plates, the ends of said offsets being open to permit the passage of air 15 into the spaces formed between said spacer plates by said cooperating grooves.

In testimony whereof I have signed my name to this specification.

JAMES W. McFARLAND.
